CLAMPING RING RELEASE MECHANISM
Richard S. Brashears, Silver Spring, Md., assignor to the
United States of America as represented by the Sec-
retary of the Navy

Filed Mar. 12, 1958, Ser. No. 721,672
8 Claims. (Cl. 102—49)

This invention relates to release mechanisms, and more particularly to a mechanism for effecting inflight release of a booster rocket from a missile.

Certain missile-booster combinations are stored in readiness for launching in a coupled state, that is, with the missile clamped to the booster so that a minimum amount of preparation time is required for delivery to the launcher. As described in U.S. patent application No. 594,067, filed June 26, 1956, by W. H. Goss et al., relating to a Guided Missile, the missile is unclamped from the booster as the missile-booster combination leaves the launcher; however, the combination remains coupled by the force of the booster impulse. During flight, as the booster thrust decays and the force between the missile and booster approaches zero, separation conditions occur, the rate of separation of course being dependent on the rate of booster thrust decay. Many test flights have indicated successful separation; however, of the portion of flights that have resulted in failure, a considerable percentage can possibly be attributed to unsuccessful separation of the booster from the missile. Test data has indicated, especially in the case of flight failures, that separation was not instantaneous, but that there was recontact between the missile and the booster.

One possible explanation advanced for the recontact was that impact between the missile and booster was due to the combination of a slow booster tail-off and pressure oscillations in the missile diffuser. It is believed that this recontact caused such misalignment of the missile as to result in flight instability.

Although it cannot be stated that a slow booster tail-off would definitely result in a flight failure, it is apparent that with an unlocked missile-booster joint and a slow booster tail-off, the missile-booster combination is on the verge of instability at separation, and the destabilizing forces will have a greater time interval in which to act.

As a solution to this problem, it was determined that since the missile and booster were held together before launching by a clamp ring, what was required was a means of releasing the clamp ring at the end of the boost phase rather than at the beginning, i.e., upon launching. Furthermore, if the clamp ring were released slightly later than the time separation would normally occur if the missile and booster were not clamped together, a tension force would be built up across the missile-booster joint as a result of the decay of thrust below the drag differential between the missile and the booster. This tension force would insure that separation proceed rapidly thus shortening the time of application of any destabilizing force by the booster on the missile, and would tend to eliminate damaging recontact between the missile and the booster.

It is an object of this invention, therefore, to provide means for effecting, at a time most favorable for rapid separation, release of a clamp ring holding together a missile and a booster.

It is also an object of this invention to provide means for effecting, as rapidly as possible, release of a clamp ring holding together a missile and a booster to mitigate the effects of any destabilizing forces imposed by the booster on the missile.

It is a further object of this invention to provide means for effecting at the end of the booster thrust phase, in-

2

flight release of a clamp ring holding together a missile and a booster.

Still another object of this invention is to provide means for preventing damaging recontact of a missile and a booster at separation.

Other objects and many of the attendant advantages of this invention will readily be appreciated as the same becomes understood by reference to the following detailed description when considered in connection with the accompanying drawings, wherein:

FIG. 1 is a side elevation of a missile and booster held together by a clamp ring, showing the location of the release mechanism;

FIG. 2 is a cross section on line 2—2 of FIG. 1 showing the general arrangement of the release mechanism and details of the clamp ring;

FIG. 3 is a longitudinal section of the sensing cylinder;

FIG. 4 is an enlarged section of the explosive cylinder on line 4—4 of FIG. 2; and

FIG. 5 is a cross section of the explosive cylinder on line 5—5 of FIG. 4.

Briefly, the present invention contemplates a sensing cylinder mounted on the booster of a missile-booster combination and actuated by pressure bled from the booster chamber. The piston of the sensing cylinder, in responding to a drop in booster pressure at boost phase termination, actuates a microswitch which closes a circuit from a thermal battery to an explosive containing cylinder that is also mounted on the booster. The latter cylinder, upon detonation, releases a scissors mechanism holding together a clamp ring that couples the missile to the booster.

Referring now to the drawings in greater detail, FIG. 1 shows a missile-booster combination 1 having a missile 2 and a booster rocket 3 held together by a clamp ring assembly 4. A release mechanism 5 constituting the present invention is mounted on the forward end of the booster 3.

The clamp ring assembly 4 is disclosed in U.S. patent application No. 594,067, filed June 26, 1956, by W. H. Goss et al. for a Guided Missile, and as seen in FIG. 2, includes a pair of companion semicircular ring sections 6 each having an internally threaded fitting 7 secured to one end thereof. A right and left screw link 8 engages each of the fittings 7 to connect the two ring sections 6. A hexagonal head 9 is provided at each end of the link 8 to facilitate wrenching for adjusting purposes. On the other end of each of the ring sections 6 is secured a bracket 10 having a pair of apertured yokes 11 formed thereon. A scissors hinge 12, having its two arms 13 and 14 pivotally connected by a pin 15, is pivotally mounted on the brackets 10 by pins 16. The scissors hinge 12 permits concentric opening of the ring sections 6 to uncouple the booster 3 from the missile 2. To insure positive opening of these ring sections, leaf springs 17 are mounted on the inner surface thereof and bear against the missile-booster combination and tend to force the ring sections 6 outwardly. The end portions of the scissors arms 13 and 14, respectively, are formed with lateral extensions 13a and 14a and are held together by an explosive cylinder assembly 100, to be hereinafter described.

As best seen in FIGS. 2 and 3, the release mechanism 5 includes a sensing cylinder assembly 20 mounted on the booster 3 by a bracket 22. The cylinder assembly 20 comprises a cylinder 24 having a first chamber 26 and a second chamber 28. A wall 30 is positioned between the two chambers 26 and 28 and has an aperture 32 extending therethrough. An end cap 34 threadably engages and closes the cylinder 24 at the end nearest the first chamber 26. An O-ring 35 is positioned between the cylinder 24 and end cap 34 for sealing purposes. A nipple 36 having an aperture 38 extending therethrough is formed on the end cap 34 and is connected to a tube 39 which trans-

mits pressure from a chamber (not shown) of the booster 3. A head cap 40 threadably engages and closes the end of the cylinder nearest the second chamber 28. A piston 42 is located in the first chamber 26 and has a stem 44 extending through the aperture 32 of the wall 30. The stem 44 is long enough to extend the full length of the cylinder 24 and through an aperture 46 in end wall 48 of the head cap 40. An annular groove 50 is formed in the piston 42 to contain a suitable packing 52. A shoulder 54 is provided on the stem 44 and bears against bearing plate 56. A spring 58 is interposed between the bearing plate 56 and the end wall 48 of the head cap 40.

Attached to the head cap 40 by bolts 60 is a housing 64 in which is mounted a microswitch 66 by means of screws 67. A bore 68 in registry with the aperture 46 is provided in the housing 64 for receiving the extension of the piston stem 44 and for containing a retainer 70. A vent hole 72 is formed in end wall 74 and communicates with the bore 68. The microswitch 66 is a normally closed switch and is actuated by a plunger 76 which is housed in a crossbore 78 formed in the housing 64. It will be seen that the relationship of the piston stem 44 to the crossbore 78 is such that the stem in its uppermost position is clear of the crossbore. This arrangement permits the retainer 70 to assume a position across the crossbore 78 to hold the plunger 76 down, thus keeping the microswitch 66 open. A detent is provided for maintaining the retainer 70 in this position by a spring loaded ball 80 riding in a groove 82 formed on the retainer. The ball 80 is located in an aperture 84 in the housing 64 and is held down by a spring 86 and a machine screw 88. A second groove 90 is formed in the retainer 70 to provide a second detent position and is located so that when the retainer is in this second detent position, the retainer will be clear of the crossbore 78. It should be noted that the bore 68 should be of sufficient length to accommodate the retainer 70 when the latter is in the second detent position.

As previously mentioned, booster chamber pressure is transmitted to the cylinder assembly 20 by means of the tube 39. This transmitted pressure acts on the piston 42 to move it against the force of the spring 58 until the end of the stem 44 contacts the retainer 70 in the housing 64. As the piston continues its movement, the retainer 70 is urged out of its first detent position, and the stem 44 eventually displaces the retainer sufficiently so that the microswitch plunger 76 will be held down by the stem 44 rather than by the retainer. The retainer 70, in being displaced, moves into contact with the end wall 74 and at the same time moves into the second detent position, that is, the ball 80 engages in the groove 90.

At termination of the boost phase, as the booster chamber pressure subsides, the piston 42 begins to reverse its movement, since the force of the spring 58 will again predominate. As the piston stem 44 retracts, the retainer 70 will remain stationary by reason of the engagement of the ball 80 in the groove 90, in the second detent position. Thus, the plunger 76 will be released when the stem 44 clears the crossbore 78. Release of the plunger actuates the microswitch 66 to close a circuit in cable 79 between a thermal battery 94 and the explosive cylinder assembly 100. Since it is desired that the microswitch 66 be actuated at a certain known value of booster pressure, the spring 58 should have a proper spring constant. In order to allow for any small inaccuracies in calibration of the spring, shims 92 may be utilized between the head cap 40 and the housing 64 for varying the loading on the spring.

The thermal battery 94 is mounted on the booster and is provided with a solid electrolyte that is melted whenever it is desired to activate the battery. This type 70 battery has a much longer shelf life than an ordinary battery and is particularly suitable for use on missiles or rockets that spend much time in storage.

The explosive cylinder assembly 100 is mounted on the booster 3, and as shown in FIGS. 2 and 4, restricts 75

movement of the scissors hinge 12 to maintain the clamping ring sections 6 in a clamped position. As best seen in FIG. 4, the explosive cylinder assembly 100 comprises a cylinder 102 having a piston 104 therein. One end of the cylinder 102 is formed with an internally threaded portion 106 into which is screwed a housing 108, a diaphragm 109 being compressed between the cylinder and the housing. The housing 108 is provided with recesses 110 and 112 at its ends, and interposed between the two recesses is a wall 114 having two apertures 116 extending therethrough. The two apertures are counterbored to form an enlarged diameter portion 118 and threads are provided on a part of the enlarged diameter portion 118 nearest the recess 110. At its opposite end the housing is threaded at 122 to receive a nut 124.

Two squibs 126 are contained in the housing 108 and conform generally to the configuration of the apertures 116 and the unthreaded part of the enlarged diameter portion 118. A plastic insulating sleeve 127 is interposed between the housing 108 and the squibs at the aperture 116, a projecting portion 128 of each of the squibs 126 extending through the aperture 116 into the recess 112 and being provided with a thin-walled brass cap 130 having external threads formed thereon. Two plugs 132, each having an aperture 134 extending therethrough and having external threads thereon, are screwed into the threaded part of the enlarged diameter portion 118, and an explosive substance 136, such as black cannon powder, is contained in the recess 110 adjacent the plugs 132 and is held in place by a diaphragm 138.

As shown in FIGS. 4 and 5, an electrical contact 140, having an externally threaded portion 142 and an internally threaded portion 144, is screwed into the housing 108. A circular insulating spacer 146 is positioned against the wall 114 of the housing 108 in recess 112 and is properly apertured to permit the projecting portion of squibs 126 and the contact 140 to project therethrough. An apertured contact plate 152 is positioned against the spacer 146 and is secured by two slotted contact nuts 156 that engage the threaded brass caps 130 on the squibs 126. As seen in FIG. 5, the plate 152 is so constructed that when properly positioned, it will not come into contact with the electrical contact 140. Two terminals 158 are provided on the plate 152 for facilitating attachment of wires 162. A screw 164 engages the internally threaded portion 144 of the contact 140 for securing a ground wire 166.

A cap 168 closes the recess 112 of the housing 108 and is clamped to the housing by the tightening of the nut 124 down on a flange 170 formed on the cap, a pin 171 projecting from the end of the housing 108 to engage in a slot 172 formed in the flange 170 for locating purposes. A setscrew is provided on the nut 124 to prevent undesired movement thereof. The top of the cap 168 is formed by an electrical connector 174 soldered thereto. After the other ends of the wires 162 and 166 are attached to the connector 174, potting compound (not shown) is injected through an aperture 178 in the wall of the cap 168 to fill the space formed by the recess 112 and the cap.

Referring again to FIG. 4, it will be seen that the piston 104 is of hollow cylindrical construction and is formed with an outer rim 180 that slides against the inside of cylinder wall 182, an end wall 184 of the cylinder 102 being provided with an aperture 186 to support the other end of the piston 104 and to permit the latter to slidably extend therethrough. Thus the piston is constrained to move within the limits imposed by the diaphragm 109 and the end wall 184. An aperture 188 is drilled through the cylinder wall 182 for venting purposes. A projecting portion 190 of the cylinder 102 extends beyond the end wall 184 and as viewed in FIG. 2 is formed with a longitudinal slot 192 that is substantially T-shaped.

It will be remembered that the explosive cylinder assembly 100 restricts movement of the scissors hinge 12 to maintain the clamping ring sections 6 in a clamped position. FIGS. 2 and 4 show the cylinder assembly 100 mounted on the booster 3 adjacent the scissors hinge 12 in such manner that the projecting portion 190 clamps together the two arms 13 and 14 by engagement of the extensions 13a and 14a in the T-shaped slot 192. While the extensions 13a and 14a are engaged in the slot 192, the piston 104, by contact with the arm ends, is forced into the cylinder 102 until the rim 180 is bearing lightly against the diaphragm 109. It will be seen then, that when the explosive substance 136 is detonated, the piston 104 will tend to be forced to the other end of the cylinder. However, because the piston bears against the scissors hinge 12, the cylinder 102 will be displaced from its original position, thus freeing the scissors hinge arms 13 and 14 to allow the ring sections 6 to spring free of the missile-booster combination.

For the purpose of preventing premature release of the hinge arms 13 and 14, a pin 194 is inserted through apertures in the cylinder 102 and the hinge arms to avert withdrawal of the extensions 13a and 14a from the slot 192.

In use, the missile 2 and the booster 3 are conveyed to the launcher in a coupled state, being held together by the clamping ring assembly 4. As part of the procedure for preparing the missile-booster for launching, the pin 194 is withdrawn from its position where it is locking the scissors arms 13 and 14 in the T-shaped slot 192 of the explosive cylinder assembly 100. At about the same time the electrolyte of the thermal battery 94 is melted by an independent heating circuit to activate the battery.

At launching, upon ignition of the booster rocket, the increased pressure in the booster chamber acts through the tube 39 to move the piston 42 against the force of the spring 58, thereby causing the piston stem 44 to displace the retainer 70 in holding the plunger 76 down to keep the microswitch 66 open. This condition is maintained throughout the boost phase until the booster thrust decays to a certain predetermined value. When this occurs, and the booster pressure drops, the force of the spring 58 returns the piston 42 to its original position thus allowing the plunger 76 to be released. This actuates the microswitch 66 which in turn closes firing circuits between the thermal battery 93 and each of the squibs 126. The squibs then detonate the explosive substance 136 to displace the cylinder 102 from its clamping position which frees the arms 13 and 14 of the scissors hinge 12. Disengagement of the scissors hinge arms from the cylinder 102 permits the clamping ring sections 6 to release under the force of the springs 17 thereby uncoupling the booster 3 from the missile 2.

Obviously many modifications and variations of the present invention are possible in the light of the above teachings. It is therefore to be understood that within the scope of the appended claims the invention may be practiced otherwise than as specifically described.

What is claimed is:

1. In combination with a missile and a booster rocket coupled in tandem by a releasable clamping ring, a mechanism on said booster rocket for effecting in-flight release of said clamping ring, comprising, means engageable with said ring and including a clamp for constraining said ring to a clamping position, said means being actuatable by an electrical impulse to release said clamp from constraint of said ring, a source of electrical energy and a switch coupled thereto, said switch being operable to transmit said electrical impulse to said means, and second means coupled to said first mentioned means and including a sensing cylinder having a spring loaded piston and a retainer, a detent for said retainer, said piston and retainer being engageable with said switch, said cylinder being responsive to pressure within said booster and operable against the force of said spring loaded piston and said re-

tainer at a predetermined value of said pressure to move said piston into an armed position wherein said mechanism is ready to release said clamping ring, said cylinder also being responsive subsequently at another predetermined value of said pressure to operate said switch.

2. The combination as claimed in claim 1, wherein said first means includes additionally an explosive device connected to said clamp and detonable upon receipt of said impulse to disengage said clamp from said ring.

3. In a releasable clamping ring arrangement for coupling a missile and a booster, a mechanism for effecting in-flight release of said clamping ring, comprising, means engageable with said ring and including a clamp for constraining said ring to a clamping position, said means being actuatable upon receipt of an electrical impulse from the booster to release said ring, a source of electrical energy, a switch and circuitry to electrically couple said source to said means, and a sensing cylinder engageable with said switch and responsive to pressure within said booster, said cylinder including a spring loaded piston and a retainer, said piston and retainer being engageable with said switch, a detent for said retainer, said cylinder being operable against the force of said spring loaded piston and retainer at a predetermined value of said pressure to place said mechanism in an armed condition wherein said mechanism is ready to release said clamping ring, said cylinder also being operable subsequently at another predetermined value of said pressure to operate said switch.

4. The apparatus as recited in claim 3, wherein said means includes additionally an explosive device connected to said clamp and detonable upon receipt of said impulse to displace said clamp from engagement with said ring.

5. In combination with a missile and a booster, and a releasable clamping ring for coupling said missile and booster in tandem relationship, said clamping ring having release arms, a release mechanism on said booster for effecting in-flight release of said clamping ring, comprising, a retaining member slidably engageable with said release arms and tending to prevent release of said ring, a cylinder connected to said member and having an explosive charge therein, said charge being detonable upon receipt of a signal to displace said member from engagement with said release arms, a battery, a switch connected to said battery, a sensing cylinder including a spring loaded piston and a retainer, a detent for said retainer, said piston and retainer being engageable with said switch, said cylinder being responsive to gas pressure within said booster and operable against the force of said spring loaded piston and retainer at a predetermined value of said pressure to place said release mechanism in an armed condition wherein said mechanism is ready to release said clamping ring, said cylinder also being operable subsequently and at another predetermined value of said pressure to close said switch to produce said signal, and circuitry to transmit said signal from said battery to said explosive cylinder.

6. In combination with a missile and a booster, and a releasable clamping ring coupling said missile and booster in tandem relationship, a mechanism on said booster for effecting in-flight release of said clamping ring, comprising, constraining means engageable with said ring and including a clamp for holding said ring in a clamped position, a battery, a switch connected to said battery and actuatable to electrically couple said battery and said constraining means, a sensing cylinder including a spring loaded piston and a retainer, a detent for said retainer, said piston and retainer being engageable with said switch, said cylinder being responsive to pressure in said booster and being operable against the force of said spring loaded piston and retainer at a predetermined value of said pressure to place said mechanism in an armed condition wherein said mechanism is ready to release said clamping ring, said cylinder also being operable subsequently and at another predetermined value of said pressure to actu-

ate said switch, whereby said electric signal is transmitted to said constraining means, thereby causing said constraining means to actuate and expel said clamp from engagement with said ring.

7. The apparatus recited in claim 6 wherein said constraining means includes additionally an explosive cylinder detonable upon receipt of said electric signal.

8. The apparatus recited in claim 6 wherein said sensing cylinder includes a piston stem on said spring loaded piston and engageable with said retainer, said retainer being engageable with said switch to keep said switch in an open position and said mechanism in an unarmed condition, said piston stem also being engageable with said switch to keep said switch in the open position and said mechanism in the armed condition, said mechanism being 10 in the unarmed condition until said first predetermined value of said booster pressure is attained, whereby said 15

first predetermined value of said pressure urges said piston and piston stem to replace said retainer in engagement with said switch thereby placing said mechanism in the armed condition, and whereby said subsequent and other predetermined value of booster pressure causes said spring loaded piston to withdraw said stem from engagement from said switch, thereby actuating said constraining means.
